(57) **CLAIM**

I claim the ornamental design for a jewelry article, as shown and described.

DESCRIPTION

FIGS. 1-18 illustrate a first embodiment of the jewelry article in which:

FIG. 1 is a perspective view of a jewelry article with an engagement band removed from a wedding band for ease of illustration;

FIG. 2 is a top view thereof;

FIG. 3 is a front view thereof;

FIG. 4 is a rear view thereof;
FIG. 5 is a left side view thereof;
FIG. 6 is a right side view thereof;
FIG. 7 is a bottom view thereof;
FIGS. 8-13 illustrate the engagement band thereof in which:
FIG. 8 is a top view thereof;
FIG. 9 is a front view thereof;
FIG. 10 is a rear view thereof;
FIG. 11 is a left side view thereof;
FIG. 12 is a right side view thereof;
FIG. 13 is a bottom view thereof;
FIGS. 14-19 illustrate the wedding band thereof in which:
FIG. 14 is a top view thereof;
FIG. 15 is a front view thereof;
FIG. 16 is a rear view thereof;
FIG. 17 is a left side view thereof;
FIG. 18 is a right side view thereof;
FIG. 19 is a bottom view thereof;
FIGS. 20-38 illustrate a second embodiment of the jewelry article in which:
FIG. 20 is a perspective view of a jewelry article with the engagement band removed from the wedding band for ease of illustration;
FIG. 21 is a top view thereof;
FIG. 22 is a front view thereof;
FIG. 23 is a rear view thereof;
FIG. 24 is a left side view thereof;
FIG. 25 is a right side view thereof;
FIG. 26 is a bottom view thereof;
FIGS. 27-32 illustrate the engagement band thereof in which:
FIG. 27 is a top view thereof;
FIG. 28 is a front view thereof;
FIG. 29 is a rear view thereof;
FIG. 30 is a left side view thereof;
FIG. 31 is a right side view thereof;
FIG. 32 is a bottom view thereof;
FIGS. 33-38 illustrate the wedding band thereof in which:
FIG. 33 is a top view thereof;
FIG. 34 is a front view thereof;
FIG. 35 is a rear view thereof;
FIG. 36 is a left side view thereof;
FIG. 37 is a right side view thereof; and,
FIG. 38 is a bottom view thereof.
Broken lines are used in the drawings to illustrate features of the jewelry article that form no part of the claimed design.

1 Claim, 14 Drawing Sheets
